[57] CLAIM

The ornamental design for combination sled and wagon for children, as shown and described.

DESCRIPTION

FIG. 1 is a top plan elevational view for a combination sled and wagon for children showing my new design; FIG. 2 is a left side elevational view thereof taken in the direction of arrow 2 in FIG. 1, the right side being a mirror image thereof;

FIG. 3 is a front elevational view thereof taken in the direction of arrow 3 in FIG. 1;

FIG. 4 is a rear elevational view thereof taken in the direction of arrow 4 in FIG. 1; and,

FIG. 5 is a bottom elevational view thereof taken in the direction of arrow 5 in FIG. 2.

FIG. 1**FIG. 2****FIG. 5****FIG. 3****FIG. 4**
